DESIGN FOR A DISPLAY CABINET

Dean T. Waddell, Greenfield, Ohio

Application February 8, 1945, Serial No. 117,821

Term of patent 7 years

(Cl. D80—11)

To all whom it may concern:

Be it known that I, Dean T. Waddell, a citizen of the United States and a resident of Greenfield, in the county of Highland and State of Ohio, have invented a new, original, and ornamental Design for a Display Cabinet, of which the following is a specification, reference being had to the accompanying drawings, which form a part thereof.

In the drawings:

Fig. 1 is a front elevational view of a display cabinet showing my new design;

Fig. 2 is a rear elevational view thereof;

Fig. 3 is a top plan view; and,

Fig. 4 is an end elevational view.

I claim:

The ornamental design for a display cabinet, as shown.

DEAN T. WADDELL.
